Arba Van Wormer INVENTOR

BY

H. G. Burns ATTORNEY.

UNITED STATES PATENT OFFICE.

ARBA VAN WORMER, OF FORT WAYNE, INDIANA.

SHUTTER FOR CINEMATOGRAPHS.

1,342,076.

Specification of Letters Patent. Patented June 1, 1920.

Application filed August 28, 1919. Serial No. 320,437.

To all whom it may concern:

Be it known that I, ARBA VAN WORMER, a citizen of the United States of America, and resident of Fort Wayne, in the county of Allen and State of Indiana, have invented 5 certain new and useful Improvements in Shutters for Cinematographs, of which the following is a specification.

This invention relates to improvements in 10 shutters for cinematographs and the object thereof is to provide a device of its class with which a reduction in the amount of flickering that generally occurs in projecting films will be accomplished.

15 The object of the invention is accomplished by the construction illustrated in the accompanying drawings in which:—

Figure 1 is an elevation showing one of a pair of coöperating disks;

20 Fig. 2 is a similar view of the other coöperating disk; and

Fig. 3 is a side view of the disks mounted in coöperative relation and shown in section on a line extending horizontally through the 25 centers of Figs. 1 and 2.

Similar characters of reference indicate corresponding parts throughout the several views and referring now to the same:

1 and 2 are shutter disks, each having a 30 central spider 3—4 respectively for its support. The hub 5 of the spider 4 is split and has a pair of lugs 6 through which a screw 7 extends so that the hub may be securely clamped upon the operating shaft 8. The 35 hub 5 has an extending sleeve 9 upon which is adjustably mounted the hub 10 of the spider 3, there being a screw 11 for securing it upon the sleeve in adjusted positions. When thus secured the disks are held in 40 parallel positions and are adjustably spaced apart.

The disk 1 has two exposure openings 12 located opposite each other and a cover blade 13 and also a shadow blade 14 that are 45 located opposite each other and between the exposure openings. The cover blade and shadow blade each have a series of concentric openings 15 with intervening opaque bars 16 between the corresponding concentric 50 openings, the outer ends of each bar of the shadow blade terminating respectively with pointed extensions 17.

The disk 2 has two exposure openings 18 located opposite each other, and a cover 55 blade 19 and also a shadow blade 20 that are located opposite each other and between the

exposure openings therein. The cover blade 19 and the shadow blade 20 each have a series of concentric openings 21 with intervening opaque bars 22 between the corresponding 60 openings, the outer ends of each bar of the shadow blade terminating respectively with pointed extensions 23.

The concentric slots of the blades of the disk 1 have the same radii as the bars of the 65 corresponding blades of the disk 2 so that the bars of the one disk will obstruct the light projected through the slots in the blades of the other disk when the two disks are positioned to turn upon a common axial center, 70 it being the intention to position the disks so that their blades are similarly posed.

In the operation of the invention the shutter is applied in connection with a cinematographic projector (not shown) and rotated 75 in the customary manner so that the light projected through the lens of the instrument will pass through the disks unobstructed during the time of the passages of the exposure openings before the lens and will become obstructed more or less during the 80 passages of the cover and shadow blades, the intention being to stop the film in the instrument from one picture to the succeeding picture during the passage of the cover blades 85 across the path of the projected light from the lens, the shadow blades serving to balance the interruption caused by the cover blades.

By constructing the cover and shadow 90 blades so that the bars of the blades of one disk will obstruct the passage of light from the lens directly through the slots in the blades of the other disk, the picture projected by the light is obliterated leaving only 95 a diffusion of light projected indirectly through the slots effecting the projection upon the screen of diffused light instead of corresponding periods of complete interruptions of projected light. Thus, in using the 100 present apparatus the contrast between the uninterrupted exposures and the obstructed periods intervening therebetween is less marked than when the ordinary device is employed, and especially is the contrast lessened by forming the slots in the blades in 105 concentric arrangement so that the movement of the bars of the blades that obstruct the light is in line with the circular motion of the disks.

More or less diffused light will be projected through the blades accordingly as the 110

disks are adjustably positioned farther apart or closer together, and such adjustments are accordingly made to suit the peculiar character of the various films.

5 The effect of the pointed extensions at the ends of the bars of the shadow blades is that the projected light becomes blended by the partial obstruction of the light afforded by the extensions as they enter and leave 10 the projected rays, thus tending to reduce the harshness of the obstruction effected by the shadow blades so that less flickering is noticeable on the screen.

What I claim is:—

15 1. In a cinematographic shutter, a pair of disks supported to rotate upon a common axial center and being adjustably positioned apart from each other, each disk having opposite exposure openings and a cover blade 20 and also a shadow blade oppositely positioned between the exposure openings, the blades of each disk having a series of concentric slots and corresponding intervening concentric bars, the bars in the blades of 25 one disk being positioned so as to obstruct the light projected through the slots of the other disk.

2. In a cinematographic shutter, two disks adjustably spaced apart and arranged 30 to rotate together upon a common axis, each disk having opposite exposure openings for unobstructed passage of light therethrough and having also a cover and a shadow blade oppositely disposed between the exposure

openings and having a series of alternate 35 slots and bars concentrically disposed, the bars of one disk being located so as to obstruct the direct passage of light through the corresponding slots in the other disks.

3. In a cinematographic shutter, two 40 disks spaced apart and arranged to rotate upon a common axis, each disk having exposure openings therein and oppositely disposed blades between the openings, the blades having a series of concentric slots 45 and intervening bars, the bars of the blades of one disk being so arranged as to obstruct the light projected through the slots in the blades of the other disk.

4. In a cinematographic shutter, a pair 50 of disks spaced apart and arranged to rotate upon a common axis, each disk having exposure openings therein and oppositely disposed blades between the openings provided with concentrically arranged bars 55 and corresponding concentric slots interveningly disposed, the ends of the bars of one of the blades of each disk having pointed extensions, the bars in the blades of one disk being so disposed as to obstruct 60 light projected through the corresponding slots in the blades of the other disk.

In testimony whereof I affix my signature in presence of two witnesses.

ARBA VAN WORMER.
